UNITED STATES PATENT OFFICE.

LEON E. RENNELL, OF ALBANY, OREGON.

CUT-OUT DEVICE FOR TELEPHONE-TRANSMITTERS.

1,251,695.

Specification of Letters Patent.

Patented Jan. 1, 1918.

Application filed March 31, 1917. Serial No. 158,939.

To all whom it may concern:

Be it known that I, LEON E. RENNELL, a citizen of the United States, residing at Albany, in the county of Linn and State of Oregon, have invented certain new and useful Improvements in Cut-Out Devices for Telephone-Transmitters, of which the following is a specification, reference being had to the accompanying drawings.

10 This invention relates to an improved cut-out device for telephone transmitters and has for its primary object to provide simple and effective means whereby a subscriber using the telephone may temporarily cut out 15 or disconnect the telephone transmitter from the circuit when he desire to converse with a person in the room without being heard by the party with whom he is conducting the telephonic conversation.

20 It is another and more particular object of my invention to provide a cut-out switch arranged in the transmitter circuit which may be arranged upon the standard of the telephone, located in a desk top, or at any 25 other convenient place.

It is also an important object of the invention to provide a device for the above purpose which is exceedingly simple in its construction, positive and reliable in practical use and may be readily applied to the ordinary telephone without necessitating any alterations in its construction or variations in the wiring system.

With the above and other objects in view, 35 my invention consists in the novel features of construction, combination and arrangement of parts to be hereinafter more fully described, claimed and illustrated in the accompanying drawings, in which,

40 Figure 1 is a side elevation of a subscriber's telephone with my improved cut out device applied thereto and showing said device in its normal position, the circuit for the transmitter being diagrammatically illustrated;

45 Fig. 2 is a similar view showing the movable element of the cut-out device shifted to position, whereby the transmitter is cut out of the circuit;

50 Fig. 3 is a section taken on the line 3—3 of Fig. 1; and

Fig. 4 is a detail perspective view of the shiftable cut-out member.

55 In the accompanying drawings, I have illustrated a telephone of the conventional type, including a base 5, a standard 6, a

transmitter head 7, and a mouth piece 8, the transmitter head being pivotally and adjustably mounted upon the upper end of the standard 6 in the usual manner. The 60 receiver and receiver hook are, of course, provided, but are not illustrated in the accompanying drawings, it being unnecessary to a clear understanding of the present invention.

65 In the transmitter head 7, the usual carbon microphone 9 is arranged having the terminals 10 and 11 respectively. One of the line wires 12 is connected to the electrode 10.

70 In the illustrated embodiment of the invention, I have shown a series of spaced contacts designated 13, 14, and 15 respectively, mounted in the standard 6 in vertical spaced relation to each other. The other line wire 16 is connected to the intermediate contact member 14 and a wire 17 connects the contact member 15 to the other electrode 11 of the microphone transmitter. A glass tube indicated at 18, containing pulverized charcoal, is arranged within the telephone standard 6, and a wire 19 extending downwardly into the charcoal is joined at one of its ends to the line wire 12. A wire 20 also extends down into the charcoal and 80 is connected to the other of the contacts 13. 85

Upon the exterior of the standard 6 of the telephone, a shiftable block 21 of insulating material is mounted between spaced guides 22. This block is provided upon its inner face with a plate of brass, copper, or other conductive metal which is disposed inwardly of the outer surface of the telephone standard. Suitable stops 23 and 24 are provided to limit the sliding movement of the block 95 21 in each direction.

When the shiftable block 21 is in the position shown in Fig. 1 of the drawings, the transmitter circuit is closed from the line wire 12 through the microphone transmitter 100 9, wire 17, contact 15, plate 22, contact 14, to the other line wire 16. Assuming that the person using the telephone desires to talk to another person in the room, in order that such conversation may not be heard by 105 the party at the other end of the line, the member 21 is shifted to the position seen in Fig. 2 and the plate 22 engaged with the contacts 13 and 14. The transmitter circuit is now shunted from the wire 16 through 110 contact 14, plate 22, contact 13, wire 20, the resistance, wire 19, to wire 12, and the wire

17 connected to the microphone electrode 11 is cut out of the circuit. It will be understood that the receiver of the telephone remains in the circuit. In this manner, the 5 transmitter may be temporarily disconnected so that the user of the telephone may freely speak without placing his hand over the mouth piece 8, and with the assurance that no sound will be telephonically transmitted to the party with whom he has been 10 talking.

From the foregoing description, taken in connection with the accompanying drawings, the construction, manner of operation, and 15 several advantages of my improved telephone transmitter cut-out device will be clearly and fully understood. It is, of course, apparent that instead of using the pulverized carbon in the container 18, various 20 other forms of electrical resistance units may be used in lieu thereof, such for instance, as a resistance wire, mercury, or a coil. It is also to be understood as within the scope of the present invention, that the 25 cut-out switch and the resistance may be arranged in various other places than upon the standard of the telephone instrument. Thus, these parts may be suitably arranged in a desk structure, a table, or a wall remote 30 from the instrument. After talking to the person in the room, the user of the telephone may reverse the slide from the position shown in Fig. 1, again placing the transmitter microphone in the circuit so that he may 35 continue his conversation with the party at the other end of the line. The device is exceedingly simple, not liable to get out of order, and requires no alterations whatsoever in the construction of the ordinary telephone instrument now in general use. The 40 form, proportion, and general arrangement of the several parts of the invention may, of course, be greatly modified and I, therefore, reserve the privilege of adopting all such 45 legitimate changes as may be fairly embodied within the spirit and scope of the invention as claimed.

As will be noted from reference to the drawings, the contacts 13, 14 and 15 are so 50 spaced that the circuit will be completed between the contacts 13 and 14 before it is broken through the contact 15. This is an important feature of the device since, if the shunt circuit were closed through the contacts 13 and 14 after the circuit had been broken through the contact 15, the switch-board operator at central would have knowledge of the operation of the cut-out switch 55

and would presume that the parties were through talking and disconnect the line. 60

Having thus fully described my invention, what I desire to claim and secure by Letters Patent is:

1. The combination with a telephone transmitter and circuit therefor, of spaced 65 contacts interposed in the transmitter circuit, a shunt for the transmitter circuit including a resistance, an additional contact connected to the resistance, and a movable switch element adapted to be engaged either 70 with the first named contacts to render the transmitter circuit operative or with one of said first named contacts and the last named contact to shunt the circuit through the resistance and cut the transmitter out of the 75 circuit.

2. The combination with a telephone transmitter and circuit therefor, of spaced contacts interposed in the transmitter circuit, a shunt for the transmitter circuit including a resistance, an additional contact 80 connected to the resistance, and a movable switch element adapted to be engaged either with the first named contacts to render the transmitter circuit operative or with one of 85 said first named contacts and the last named contact to shunt the circuit through the resistance and cut the transmitter out of the circuit, said switch element engaging the latter contact prior to the breaking of the 90 transmitter circuit through the first named contact.

3. The combination with a telephone instrument having a transmitter and circuit therefor, of spaced contacts mounted in the 95 standard of the instrument and connected in the transmitter circuit, a resistance unit mounted within the standard and connected in the transmitter circuit, an additional contact secured in the standard and connected 100 to said resistance, and a frictionally held shiftable switch element mounted on the standard and adapted to engage the first named contacts to close the transmitter circuit, said element being shiftable to engage 105 the last named contact and break the circuit through the first named contacts to shunt the circuit through the resistance whereby the transmitter is cut out of the circuit.

In testimony whereof I hereunto affix my 110 signature in the presence of two witnesses.

LEON E. RENNELLS.
